ARITHMETICAL TOP AND DICE GAME

Application filed May 2, 1929. Serial No. 359,972.

This invention relates to improvements in games and has special reference to an arithmetical game that can be played by means of specially marked dice and a special top.

5 It is the object of this invention to produce an educational game that will afford amusement and entertainment for children and grown people and which at the same time will give the participants an extensive practice in 10 arithmetic.

The game apparatus, briefly described, consists in a piece of cardboard or other suitable material whose surface is artistically ornamented and on which is outlined a tortuous 15 path. This path is bordered on one side by a row of stones which are referred to as milestones. In the example given, there are one hundred fifty-five stones. The first stone is numbered 1 and the other eleven stones are 20 numbered 2 to 12, inclusive. The remaining stones are numbered from 0 to 12, in groups, there being eleven such groups besides the first group which contains only twelve stones. Each player is provided with a marker, which 25 may be a checker of a certain color, each player having a marker of a different color. The moves are determined in the following manner. A cube of solid material of a size and shape resembling a dice is provided with 30 one arithmetical sign on each side, instead of the ordinary spots. Each of the six sides is marked with one of the arithmetical signs: +, -, × or ÷ and therefore when the cube is rolled it will stop with one of these signs 35 exposed on its upper side. Instead of a solid cube, a square or octagonal top can be used and the sides thereof be marked with the arithmetical signs. If the players have any 40 preference, they may use either the dice or the top and it is also permissible to use two dice or two tops or a dice and a top; each player thereby obtaining the privilege of selecting 45 for his operation the sign that will be most advantageous. This gives practice in quick mental arithmetic as the player must decide 50 quickly which one of the alternate operations he desires to adopt. Instead of dice or a top, it is also possible to determine the arithmetical operation by any other suitable means of chance, such as by having a plurality of

cards, each of which has one arithmetical sign and selecting one or two at random. For the purpose of explanation it will be assumed that the arithmetical operations are determined by means of a four-sided top.

When the top is spun it will come to rest with one of its four sides on top and the arithmetical sign on this side will determine the operation. When the play starts the first player places his marker on the stone numbered 1 and spins the top. If the top stops with sign + on top, the player will move his marker 1+1 or two spaces because when the game starts, all of the markers are assumed to be located on stone 1 and the rule is that the player scores the sum, difference, product or quotient obtained by the arithmetical operation indicated in which the number on the nearest rival's space is used as the first numer in the example. The order of the numbers are, of course, of importance only in division and subtraction. If the sign had been - instead of + the score would be 1-1=0 and the player would fail to score. After the markers have all left the first space, the score may vary from minus 12 to plus 144 and may also be a mixed number or a fraction. If the score is a mixed number, the player moves the number of spaces represented by the nearest whole number and if it is a fraction, the same is true. Thus, if the score is less than one-half, the player cannot move; if it is one-half or more, he moves one space. In a score represented by a mixed number in which the fraction is one-half the player scores the next higher number, thus 3÷2=1½, the player will then move two spaces.

After the first move has been made, the other player puts his marker on space number 1 and chooses between rolling the dice and spinning the top. Let us assume that the dice stops with the plus side up and that the first player's marker is on space number 2, the move will then be determined by adding 2 to 1 which will give 3 as the sum. The second player then moves his marker to space number 4. If a third player takes part, he proceeds as the other two, but his moves are determined by using the number of the space

on which the marker of the player nearest to him rests as the first number in the problem by means of which he determines his moves. In this way any number of players can take part. If the operation indicated is subtraction and the subtrahend is larger than the minuend the player must move his marker rearwardly a number of spaces equal to the difference between the numbers. The above description gives a fair idea of the manner in which the game is played and for the purpose of describing the same and the apparatus more in detail, reference will now be had to the accompanying drawing in which the preferred embodiment of the apparatus has been illustrated, and in which:

Fig. 1 is a drawing showing the upper face of the board;

Fig. 2 is a perspective view of a dice employed in this game;

Fig. 3 is a development of the surface of the dice; and

Fig. 4 is a perspective view of a top employed as a substitute for the dice.

In Fig. 1 of the drawing I have shown a representation of the board on which the game is played. The path is represented by letter P. This path is bordered on one side by a larger number of spaces S which represent stones. The path is supposed to start at the cave C and to end at the small house H. In the drawing I have shown one hundred fifty-five spaces or stones. The stone nearest the cave is numbered 1 and each stone is numbered in succession from 1 to 12. The thirteenth stone from the beginning is numbered zero and stones 14 to 25 are numbered 1 to 12. The remaining spaces or stones are numbered 0 to 12. In the example shown there is one group numbered 1 to 12 and eleven groups numbered 0 to 12, but any other number of groups may be used. It is evident that the groups may contain a larger or a smaller number of spaces, but the number 12 has been chosen because the multiplication tables do not usually go higher than 12.

The central square space Q may have the rules printed thereon and may be used for any other purpose. The dice shown in perspective in Fig. 2 and shown developed in Fig. 3 differs from the ordinary dice in this, that the sides are each provided with one of the arithmetical signs instead of dots. The top shown in Fig. 4 has the two invisible sides marked $\times$ and $\div$ and therefore when it comes to rest one of the signs will always be visible on the upper or top side of the top.

Having described my invention what is claimed as new is:

1. An arithmetical game comprising, a chart having a single continuous curved path outlined thereon, said path being divided into a plurality of spaces, each of which is numbered, said numbers comprising a plurality of similar groups, two markers, each of which

serves to identify a numbered space, and means having areas provided with indicia representing the four arithmetical signs for determining by chance the arithmetical operation to which the two numbers corresponding to the positions of the markers must be subjected so as to determine the number of spaces each player may move his marker.

2. An arithmetical game comprising, a chart having a single continuous curved path outlined thereon, said path being divided into a plurality of spaces, each of which is numbered, said numbers recurring in a plurality of similar groups, two markers, each of which serves to identify a numbered space, and means comprising a top having areas provided with indicia representing the four arithmetical signs for determining by chance the arithmetical operation to which the two numbers corresponding to the positions of the markers must be subjected so as to determine the number of spaces each player may move his marker.

3. An arithmetical game comprising, a chart having a single curved path outlined thereon, said path being divided into a plurality of spaces, said spaces forming a plurality of groups, the spaces comprising the groups being numbered, the same numbers being used for each group, markers for identifying some of the numbered spaces, and means for determining by chance the arithmetical operation to which any two of the numbers identified are to be subjected for the purpose of determining the number of spaces one of the markers is to be moved.

In testimony whereof I affix my signature.

VERTNER D. BRITTINGHAM.
